UNITED STATES PATENT OFFICE

2,050,036

COATING APPARATUS

John J. Boax, McKeesport, and John A. Miller,
Brentwood, Pa., assignors to National Tube
Company, a corporation of New Jersey

Application March 26, 1935, Serial No. 13,134

3 Claims. (Cl. 91—25)

This invention relates to a coating apparatus and more particularly one which is adapted for applying a liquid coating medium to the outer surface of cylindrical objects such as pipes, tubes, 5 bars, wires and the like.

It is one of the objects of the present invention to provide a novel coating apparatus of the class described which will rapidly and automatically apply a uniform film of coating material on the 10 outer surface of the object, and one which is at the same time susceptible to rapid adjustment over a relatively wide range of sizes.

Another object is the provision of an apparatus of the class described which enables the complete 15 removal of scale and foreign matter from the work-piece before the coating medium is applied, thus presenting a clean surface to which it readily adheres, and eliminating "lumps" and "pimples", which are encountered when using the devices of 20 the prior art.

A further object is to provide a novel coating apparatus in which its entire working zone is enclosed in such fashion that none of the coating medium can escape, and at the same time eliminating the fire hazard which is always present if 25 a spray applicator is used.

These and further objects will be apparent after referring to the drawings, in which:

Figure 1 is a plan of the apparatus of the 30 invention.

Figure 2 is a side elevation.

Figure 3 is an enlarged fragmentary elevation.

Figure 4 is an enlarged sectional elevation.

Figure 5 is a sectional view on the line V—V of 35 Figure 4.

Figure 6 is an enlarged sectional elevation of a modified form of the invention.

Figure 7 is a sectional detail taken on the line 40 VII—VII of Figure 6.

Referring more particularly to the drawings, the numeral 2 designates a pair of spaced pedestals which are apertured-in-line, as at 3. A bearing 4 is disposed in each of the apertures 3 to rotatably support a shaft 5 which extends 45 through and between the pedestals 2. This shaft 5 carries a pair of eccentrics 6, one of which is disposed within each of the pedestals. A vertically slidable block 7 is disposed in each of the pedestals and are each apertured as at 9 to receive one of the eccentrics 6. These vertically 50 slidable blocks 7 carry between them a bed 10 which is provided with a pair of spaced uprights 12, the latter being apertured-in-line, as at 13. An antifriction bearing 14 is disposed in each of 55 the apertures 13 for rotatably supporting a spin-

dle 15 which is provided with a relatively large central hollow bore 16. This spindle 15 is provided between its bearings 14 with a pair of spaced plates 17 between which there extends a plurality of ribs, as at 18. Each of the plates 17 carries a 5 plurality of lugs 19 between the ribs 18 which extend laterally toward the adjacent bearing 14. These lugs 19 are apertured, as at 20, in order that each may carry a radially extending adjusting screw 21, each of which is provided on its end 10 adjacent the spindle 15 with a tip, as at 22, which seats in a recess 23 in the latter.

The plates 17 are apertured between each of the lugs 19 and the spindle 15, as at 24, to accommodate one end of a U-shaped trough 25, which 15 opens toward the spindle. Each of these U-shaped troughs 25 carries a lug 26 on each of its ends which is recessed, as at 27, and apertured in alignment with the adjusting screws 21, as shown at 28. A nut 29 is disposed in each of the 20 recesses 27 for screw-threaded engagement with each of the adjusting screws 21.

Referring to Figure 4 of the drawings, it will be readily seen that the adjusting screws 21 may be conveniently manipulated to adjust the radial 25 disposition of the U-shaped troughs 25 with respect to the central bore 16 of the spindle 15. Referring to Figure 5, each of the U-shaped troughs 25 is provided with a bushing 30 which seats therein and has on its end adjacent the 30 opening thereof a head 31. Each of these bushings 30 has a wedge-shaped recess 32. The U-shaped troughs 25 are adapted to carry a plurality of brushes 33, the bristles of which are held in a brush socket 34 which carries a wedge-shaped 35 extension 35, the latter seating in the wedge-shaped recess 32 in the bushings 30.

Referring again to Figure 4 of the drawings, the bed 10 carries a motor base 36 to which there is secured an electric motor 37. This electric 40 motor 37 carries on its shaft a pinion 38 which meshes with a gear 39, the latter being secured to an extension 40 on one end of the spindle 15.

One end of the shaft 5 is extended in a similar manner and has secured thereto a worm gear 41. 45 This worm gear 41 is encased in a housing 42 which carries a rotatable shaft 43. This rotatable shaft 43 carries a worm 44 which meshes with the worm gear 41 on the shaft 5. A hand-wheel 45 is secured to the shaft 43 for permitting the rotation of the worm 44 to impart similar motion to the shaft 5, and the consequent rotation of the eccentrics 6 to raise the sliding blocks 7 and in this way vertically adjust the disposition of the bed 10 and accordingly the spindle 15. Thus, 50 55

the hollow bore 16 of the spindle 15, which forms the line of pass of the work-piece to be coated, is rendered vertically adjustable to the remainder of the apparatus.

5 A tank 50 is disposed adjacent one of the pedestals 2 and contains a quantity of liquid coating medium, as at 51, which may be oil, wax, paint or any other suitable material. The tank 50 is provided with a vertical extension 52 which 10 carries an upper reservoir 53 at a level substantially above the spindle 15 on the adjacent bed 10. This upper reservoir 53 is furnished with coating medium from the tank 50 through a pipe 54 in which there is connected a pump 55 suitably 15 driven by an adjacent motor 56. Upon the energization of the motor 56 coating medium in the tank 50 is pumped to the upper reservoir 53, its level being satisfactorily maintained, as at 58. The upper reservoir 53 is provided with a dispensing chute 59 which carries a plurality of downwardly extending wires (not shown), in order that the liquid may travel downwardly by capillary action and flow onto the surface of a work-piece progressing through the hollow bore 25 16 of the spindle 15.

A stand 61 is disposed adjacent the tank 50 and carries a pair of pinch-rolls 62, at least one of which is driven by an adjacently disposed motor 63 to feed the work-piece forwardly.

30 As shown in Figure 3, an air blast ring 64 is disposed on the side of the stand 61 which is remote from the tank 50 and is so shaped as to provide a line of pass which is of substantially the same size, and in alinement with the pass of the 35 pinch-rolls 62. This air blast ring 64 is supplied with compressed air under suitable pressure through a pipe 65 to clean the entire outer surface of the work-piece of scale, dirt, etc.

A plurality of stands 66 is provided on the side 40 of the air blast ring 64 which is remote from the stand 61 and each carries a conveyor roll 67, some of which are individually driven by adjacent motors 68.

45 As shown in Figure 1, a stand or rack 71 is disposed adjacent the stands 66 carrying the rolls 67 to provide storage for a quantity of work-pieces X. This permits the work-pieces to be handily disposed upon the rolls 67 and fed into and through the hollow bore 16 of the spindle 15, 50 receiving on its way a quantity of coating liquid from the wires (not shown) and the dispensing chute 59 of the upper reservoir 53. As the work-piece is moved through the hollow bore 16 of the spindle 15 the brushes 33 evenly distribute the 55 coating liquid over its length in the form of a film.

A stand 72 is disposed adjacent the pedestal 2 which is remote from the tank 50 and carries a pair of pinch-rolls 72^a, at least one of which is 60 driven by an adjacently mounted motor 73. A plurality of stands 74 are mounted on the other side of the stand 71 and each is provided with a roll 75, some of which are individually driven by an adjacently disposed motor 76.

65 A plurality of vertical uprights 78 are disposed adjacent the stands 74 and rotatably support a shaft 79 which extends in the direction of travel of the work-piece X, although laterally spaced therefrom. This shaft 79 is provided with a 70 plurality of trip levers 80 which extend between and beneath the line of pass of the rolls 75 on the stands 74. As shown in Figure 2, an air cylinder 81 is mounted adjacent a stand 74 and provided with a linkage 82 in order to partially 75 rotate the shaft 79 and thus, by means of the

trip levers 80, remove a work-piece X which may be disposed on the rolls 75, and permit the same to roll transversely onto the stand 78. The air cylinder 82 is operated by the contact of the work-piece X with a control lever 83 which supplies 5 air to the cylinder 81 through a suitable pipe (not shown).

Referring to Figures 6 and 7 of the drawings, a modified form of the invention is disclosed. According to this embodiment, a bed 90 is disposed upon the sliding blocks 7 in the pedestals 2 in lieu of the previously described bed 10. The bed 90 is provided with a pair of spaced uprights 91 which are apertured in alinement as at 92. A bearing 93 is disposed in each of the apertures 15 92 to rotatably support a pair of alined sleeve sections 94. The alined sleeve sections 94 are provided on their adjacent ends with inwardly extending rings 95 which are connected together in any suitable manner to provide a unitary construction. The rings 95 are so formed and connected as to provide a continuous recess 96. Communication into and out of this continuous recess 96 is afforded by means of apertures 97 in the rings 95, which are in alinement with each other. 25

A sleeve 98 is disposed in each of the apertures 97 in the rings 95 of the sleeve sections 94, and a shaft 99 is journaled in each pair thereof. A plurality of pinions 100 are disposed in the recess 96 and each secured to one of the shafts 99. An L-shaped bearing section 102 is connected to the outside and adjacent ends of the sleeve sections 94 in such manner as to provide a continuous opening which communicates with the continuous recess 96. A ring 103 is rotatably carried 35 by the bearing sections 102 and has an integral inwardly projecting toothed ring 104 which engages the pinions 100. A worm gear ring 105 is connected to the outside of the ring 103, as shown at 106. A tray 108 is connected between the 40 vertical uprights 91 of the bed 90 and supports a shaft 109 which is journaled for rotation therein. A worm 110 is secured to the shaft 109 in such manner as to engage the worm gear ring 105 on the ring 103. 45

The shaft 109 is suitably driven to rotate the ring 103 with respect to the sleeve sections 94 and drive the pinions 100 on the shafts 99 by means of the inwardly projecting toothed ring 104. 50

A worm gear ring 115 is connected to one of the sleeve sections 94, as shown at 116. A shaft 117 is journaled in the tray 108 and has secured thereto a worm 118 which engages the worm gear ring 115. The shaft 117 is suitably driven to rotate the connected sleeve sections 94 through the worm gear ring 115. 55

An extension 123 is connected, as at 124, to the outside end of each of the sleeve sections 94, and each is provided with a pair of diagonally opposed boss portions 125, which are radially apertured as at 126. A shaft 127 is slidably disposed in each of the apertures 126 and each carries on its radially inward end a frame 128. A shaft 129 is journaled in each of the frames 128 and each 60 carries a rotary brush 130 whose outside is preferably but not necessarily concaved in the direction of its axis of rotation. A setscrew 131 is threaded into each of the boss portions 125 of the sleeve extensions 123 to secure the shafts 127 in 70 radially adjusted position in the apertures 126. The shafts 129 are connected to the shafts 99 in the sleeves 98 in the recesses 96 in the rings 95 by means of flexible driving connections 133. These flexible driving connections 133 are thus 75

operated by the shaft 109 carrying the worm 118, and the aligned sleeve sections 94 are rotated by the shaft 117 carrying the worm 118. A conical shroud 134 is assembled around the sleeve sections 94 and provided at each of its ends with an aperture 135.

Referring to Figure 6 of the drawings, an annular rubber wipe 138 is disposed in the aperture 135 which is intended as the introductory opening of the apparatus of the invention. In addition, a similar wipe 137 is secured to the inner ends of the inwardly extending rings 95 of the sleeve sections 94. A series of coils 138 are mounted within the cylindrical shroud 134 immediately adjacent the opening 135 which is provided with the wipe 136. A plurality of inwardly projecting spray nozzles 139 are provided on the inner sides of the coils 138 and the latter supplied with coating medium through a suitable pipe (not shown) and under a satisfactorily regulated pressure.

A tray 104 is disposed between the spaced uprights 91 for the purpose of catching and retaining superfluous coating medium, which is indicated at 141.

Whichever embodiment of the device of the invention is used, a very uniform and thin film of coating medium will be provided on the outside of the work-piece X. If the work-piece X is susceptible to coiling, or reeling, the rolls 67 and 15 and the pinch rolls 62 and 72 may be dispensed with, or modified, to accommodate such a mode of handling.

While we have shown and described several embodiments of our invention, it is to be understood that we do not wish to be limited exactly thereto, since various modifications may be made without departing from the scope of our invention, as defined by the following claims.

40 We claim:

1. A coating apparatus comprising, in combination, a sectional and rotatable drum, at least one brush carried on the inside of said sectional

and rotatable drum in a radially adjustable manner, means for rotating said drum, at least one rotatable shaft carried by said drum, a flexible driving connection between said brush and said rotatable shaft, means for rotating said rotatable shaft through said flexible driving connection, means for applying a coating medium to a work-piece, means for moving said work-piece through said rotatable drum and in contact with said brush, and a shroud for enclosing said rotatable drum and said means for applying a coating medium, said shroud having apertures to permit the movement of said work-piece therethrough.

2. A coating apparatus comprising, in combination, a vertically adjustable support, a sectional and rotatable drum horizontally mounted on said support, at least one brush carried on the inside of said sectional and rotatable drum in a radially adjustable manner, means for rotating said drum, at least one rotatable shaft carried by said drum, a flexible driving connection between said brush and said rotatable shaft, means for rotating said rotatable shaft through said flexible driving connection, means for applying a coating medium to a work-piece, means for moving said work-piece through said rotatable drum and in contact with said brush, and a shroud for enclosing said rotatable drum and said means for applying a coating medium, said shroud having apertures to permit the movement of said work-piece therethrough.

3. A coating apparatus comprising, in combination, a rotatable drum, at least one brush carried on the inside of said rotatable drum in a radially adjustable manner, means for rotating said drum, at least one rotatable shaft carried by said drum, a flexible driving connection between said brush and said rotatable shaft, and means for rotating said rotatable shaft through said flexible driving connection.

JOHN J. BOAX.
JOHN A. MILLER.
